UNITED STATES PATENT OFFICE.

JOHN YOUNGBERG, OF GALVA, ILLINOIS.

IMPROVED WEATHER-STRIP FOR DOORS.

Specification forming part of Letters Patent No. **39,983**, dated September 15, 1863; antedated December 8, 1861.

To all whom it may concern:

Be it known that I, JOHN YOUNGBERG, of Galva, in the county of Henry and State of Illinois, have invented a new and useful Improvement in Weather-Strips for Doors; and I do hereby declare that the following is a full, clear, and exact description of the same, reference being had to the annexed drawing, making a part of this specification, and to the letters of reference marked thereon.

The object of this invention is to close the joint between the bottom of the door and the sill; and it consists of a vertical plate riveted to a piece of india-rubber, which is secured to the sill and extended across the bottom of the door on the inner side in such a manner that the joint is kept tight when the door is closed, and when the door is opened the strip is pressed back and down, and retained in a horizontal position under the door until the closing of the latter permits it to rise and assume the vertical position in which it closes the joint.

To enable others skilled in the art to make and use my invention, I will proceed to describe its construction and operation.

The drawing represents a door with the weather-strip of my invention attached. The lines in black show its position when the door is closed, and those in red show its position when the door is open.

The inner sill is somewhat lower than the outer to permit the easy passage of the door over the weather-strip when it is laid flat on the sill, and it has a groove, *a a*, into which the edge of a piece of vulcanized india-rubber, *b b*, extending across the width of the door-frame, is secured by screws or cement. The upper edge of the india-rubber is riveted to a sheet-metal clamp, *c c*, which ex-

tends across the door. The ends of the india-rubber are fastened to the frame at *d* and *e*, which causes the weather-strip to retain a vertical position, pressing against the bottom of the door, when it is not otherwise and forcibly pressed back and down by the opening of the door. As will be particularly seen in the red lines, the outer part of the lower edge of the door at *f* is chamfered away for the purpose of easily pressing the weather-strip down when the door is opened. The buttons *g* and *h* may be turned over the strip when it is desired to keep it down with the door closed.

The operation of the invention is simple. The strip is opened by the opening of the door, which it presses down and causes it to lie flat on the sill, and the elasticity of the india-rubber causes it to rise immediately on the closing of the door, and keeps it pressed tightly on the joint of the door and sill. As it is placed on the inner side, it catches any water that may be admitted by the imperfections of the door, and it is not liable to injury by the accumulation of ice in sleety weather, and being of vulcanized india-rubber it is not affected by heat or cold in the ordinary variations of temperature.

I claim as my invention and desire to secure by Letters Patent—

The construction of a weather-strip, as described, of india-rubber, stiffened by a plate in such a manner that it will be opened by the opening of the door and closed by its own elasticity when the door is closed.

JOHN YOUNGBERG.
